UNITED STATES PATENT OFFICE.

JOSEPH V. ROBINSON, OF BRANFORD, CONNECTICUT.

AUTOMATIC ALINING DEVICE FOR THE CAR-COUPINGS OF RAILWAY-CARS.

1,245,796

Specification of Letters Patent.

Patented Nov. 6, 1917.

Application filed June 11, 1914, Serial No. 844,544. Renewed September 13, 1917. Serial No. 191,812.

To all whom it may concern:

Be it known that I, JOSEPH V. ROBINSON, a citizen of the United States, and a resident of Branford, county of New Haven, State of Connecticut, have invented certain new and useful Improvements in Automatic Alining Devices for the Car-Couplings of Railway Cars, of which the following is a specification.

The object of my invention is to provide an improved alining device for the car couplers of railway cars in which an automatic trainpipe connector is used to automatically aline the car couplers of opposing cars so that such couplers will readily couple on abrupt curves and under other conditions where, if not provided with my improvement, they would fail to connect, and in which the trainpipe connector operates also to couple the hose of the car to which my improvement is applied.

The well-known, M. C. B. or Janney type of car coupler is designed to couple on curves of only 14 degrees or under, and as much sharper curves are not at all uncommon in ordinary service, many conditions are encountered under which the present car couplers will not operate. To effect coupling under these conditions, radial draft gears by which the coupler is caused to remain always in the center of the track, have been designed. But these constructions are necessarily unwieldy and of numerous parts, are costly and to be successfully used require a marked departure from present standards.

My improvement gives to the usual or standard form of car coupler a gathering range of more than twice its present range, without adding any complication to the coupler proper or altering its contour and in this way the efficiency of the coupler is greatly improved and its interchangeability unimpaired.

With these objects in view, my invention consists of the combinations, constructions and improvements hereinafter described, pointed out in the appended claims and illustrated in the accompanying drawings, in which

Figure 1, is a side elevation of my improvement; Fig. 2, is a front face view of my improvement; and Fig. 3, is a plan view showing two car couplers equipped with my improved alining device in the act of coupling, and

Fig. 4, is a rear view of the construction shown in Fig. 2.

Referring to the drawings: The usual M. C. B. type of car coupler A, I provide with an integral lug 10, to which I secure as by bolts 11 a two-piece bracket B, comprising halves 27. The bracket is provided with an opening 12 through which extends a hollow body member C, upon the forward end of which is mounted the guiding means comprising prongs 13 and coupling head 14, of my automatic alining device.

As shown particularly in Figs. 1 and 3, the prongs 13 extend considerably in advance of the knuckle 15 of the car coupler and flare outwardly to a considerable extent. It is by this means that the couplers A of opposing cars are gathered into alinement when coupling on a sharp curve or when for other causes they are disaligned.

During this operation the couplers may readily shift laterally in their carrier-irons 16, as usual. These irons I show as being of one of the well-known forms though it would facilitate the operation of my improvement if carrier-irons having rollers or other means for lessening the friction between them and the shank of the couplers A, were used.

To prevent any relative lateral movement of the body member C and the coupler A during the act of coupling, I provide the member with a flange or projection of greater lateral width than vertical width, and provide each of the halves of the bracket B, with coöoperating laterally extending flanges or projections 18 of the same general dimensions as the flanges 17. Through slots 19, on either side of the body C, I pass a pivot bar 20, assembling on it as it passes through the body a rearwardly extending tie rod or stem 21 and journal the projecting ends 22 of the pivot bar in bearings 23, formed in each of the halves of the bracket B. When thus mounted the pivot bar may oscillate freely in the vertical plane while the tie rod 21, being journaled at 24 on the pivot bar, may oscillate freely in the horizontal plane.

To resist such oscillation of the pivot bar and tie rod 20 and 21, I provide a pair of helical springs D, and these I interpose between an abutment 25, loosely mounted upon the rear end of the tie rod 21 and the flange 17, suitable seats 26 being provided on the flange 17 and abutment 25 to hold the

springs in place. A nut 28 threadingly connected with the tie rod 21 locks the abutment in position and constitutes the means for placing the springs D under the compression required to hold the flanges 17 firmly against the projections 18 of the bracket and yieldingly maintain the body member C and coupling head 14 in normal horizontal position.

10 The pressure of the springs D against said projections, is of such extent that the body C cannot move laterally or sidewise relative to the coupler, though it may move vertically relative thereto, while the guiding prongs 13 are shifting opposing car couplers A and coupling heads 14 into alinement, as shown in Fig. 3. But after the couplers and coupling heads are brought into alinement and the cars move into the coupled position, the 20 body C and of course the coupling heads 14 move rearwardly relative to the car coupler A, which operation will also move the flanges 17 away from the projections 18 sufficiently to permit universal movement of 25 the coupling heads 14 relative to the car couplers.

The automatic coupling of the usual train pipe hose I accomplish simultaneously with the coupling of the cars, by perforating the 30 coupling head 14 at 29 and providing the body C with a hollow curved fitting or fluid conduit 30, one end of which is pressed into the coupling head 14 and the other end of which received the usual train pipe hose 31, 35 as at 32. A suitable gasket 33 is mounted in the curved fitting and is compressed as the cars couple, providing an efficient and dependable joint which will be tight under all conditions of service.

40 In this manner automatic connection of the various steam and air pipes of a car may be readily accomplished by my improved alining device for car couplers, and I have therefore produced a common means for 45 automatically alining the car couplers of opposing cars and for automatically and simultaneously connecting the train pipe hose of such cars.

Having thus described my said invention, 50 what I claim as new and desire to secure by United States Letters Patent is:—

1. The combination with a car coupler, of an automatic train pipe connector for alining said coupler with a mating coupler and 55 for automatically connecting the train pipe hose of the cars carrying said couplers said connector comprising a coupling head positioned below said car coupler and provided with flaring guiding means for gathering 60 said car coupler and mating coupler into alinement, a yieldable member also below said car coupler and by which said coupling head is carried, and means for locking said member against lateral movement relative

to said car coupler when the latter is disengaged from said mating coupler. 65

2. The combination with a car coupler, of an automatic train pipe connector for alining said coupler with a mating coupler and 70 for automatically connecting the train pipe hose of the cars carrying said couplers, said connector comprising a bracket secured to said car coupler and extending therebelow, and a member below the car coupler and extending forwardly of said bracket and carrying a coupling head, the member being adapted under certain conditions to move universally relative to said car coupler and under other conditions to move only in the vertical plane relative to said car coupler, 75 whereby said coupler is alined with the mating coupler in service.

3. The combination with a car coupler, of an automatic train pipe connector for alining said coupler with a mating coupler and 80 for automatically connecting the train pipe hose of the cars carrying said couplers, said connector comprising suitable guiding means, a member yieldable universally relative to said car coupler, when the latter is 85 engaged by a mating coupler and by which said guiding means are carried, and means for resisting, when said coupler is uncoupled, the lateral movement of said member sufficiently to cause said car coupler to be 90 shifted into alinement with said mating coupler when said guiding means engage on a curve.

4. The combination with a car coupler, of an automatic train pipe connector for alining 100 said coupler with a mating coupler and for automatically connecting the train pipe hose of the cars carrying said couplers, said connector comprising suitable guiding means, a member yieldable universally relative to said car coupler, when the latter is engaged by a mating coupler and by which said guiding means are carried, means for resisting, when said coupler is uncoupled, the lateral movement of said member sufficiently to cause the coupler to be shifted 105 into alinement with said mating coupler when said guiding means engage on a curve, and means for varying the force of said resisting means. 110

5. The combination with a car coupler, of an automatic train pipe connector for alining 115 said coupler with a mating coupler and for automatically connecting the train pipe hose of the cars carrying said couplers, 120 said connector comprising a bracket secured to said car coupler and positioned therebelow, a member also below said car coupler and extending forwardly of said bracket, and a spring for resisting, when said coupler is uncoupled, the lateral movement of said member sufficiently to cause the coupler to be shifted 125 into alinement with said mat-

- ing coupler when said guiding means engage on a curve, said member being yieldable relative to the coupler when the latter is engaged by a mating coupler.
6. The combination with a car coupler, of an automatic train pipe connector for alining said coupler with a mating coupler and for automatically connecting the train pipe hose of the cars carrying said couplers, said connector comprising a bracket secured to said car coupler and positioned therebelow, a member also below said car coupler and extending forwardly of said bracket, and a spring at the rear of said bracket and acting against said member for resisting, when said coupler is uncoupled, the lateral movement of said member sufficiently to cause the coupler to be shifted into alinement with said mating coupler when said guiding means engage on a curve, said member being yieldable relative to the coupler when the latter is engaged by a mating coupler.
7. The combination with a car coupler, of an automatic train pipe connector for alining said coupler with a mating coupler and for automatically connecting the train pipe hose of the cars carrying said couplers, said connector comprising a bracket secured to said car coupler and positioned therebelow, a member also below said coupler and extending forwardly of said bracket and carrying a coupling head provided with suitable guiding means, a projection on said member which projection bears against said bracket, and a spring acting against said projection to hold it against said bracket with sufficient force to cause said car coupler to be shifted into alinement with a mating coupler when said guiding means engage on a curve.
8. The combination with a car coupler, of an automatic train pipe connector for alining said coupler with a mating coupler and for automatically connecting the train pipe hose of the cars carrying said couplers, said connector comprising a bracket secured to said car coupler and positioned therebelow, a member also positioned below said coupler and extending through said bracket and forwardly thereof and carrying a coupling head provided with suitable guiding means, laterally extending projections on said bracket whereby the lateral width of the base of the bracket is greater than the vertical width, lateral projecting flanges on said member whereby the lateral width of one end of the member is greater than the vertical width thereof, a stem extending rearwardly of said bracket and said flanges and carrying at its rear end an abutment, and a spring interposed between said abutment and said flanges for holding said flanges against said projections with sufficient force to cause said car coupler to be shifted into alinement with a mating coupler when said guiding means engage on a curve.
9. The combination with a car coupler, of an automatic train pipe connector for alining said coupler with a mating coupler and for automatically connecting the train pipe hose of the cars carrying said couplers, said connector comprising suitable guiding means, a member yieldable universally relative to said car coupler, when the coupler is engaged with a mating coupler and by which said guiding means are carried, means for resisting, when said car coupler is uncoupled, the lateral movement of said member sufficiently to cause the coupler to be shifted into alinement with said mating coupler when said guiding means engage on a curve, a fluid conduit connected with said coupling head, and a flexible pipe for connecting said conduit with the train pipe of the car.
10. The combination with a car coupler, of means for automatically alining said coupler with a mating coupler, said means comprising suitable guiding prongs positioned below said car coupler and extending forwardly and diverging laterally thereof, a yieldable support for said guiding means also positioned below said coupler, and means for preventing said support from moving relative to said car coupler except when said car coupler and said mating coupler are engaged.
11. The combination with a car coupler, of means for automatically alining said coupler with a mating coupler, said means comprising suitable guiding mechanism, a yieldable support positioned below said car coupler and carrying said guiding mechanism, a bracket connected with said car coupler for carrying said support, the latter being freely movable relative to the bracket when the car coupler is engaged with a mating coupler, and means for resisting, when said car coupler is uncoupled, the lateral movement of said support relative to said car coupler sufficiently to shift the coupler into alinement with said mating coupler when said guiding means engage on a curve.
- In testimony whereof, I have hereunto set my hand in the presence of two witnesses.
- JOSEPH V. ROBINSON.
